APPLICATOR FOR MEDICAMENTS OR THE LIKE

Neil S. Waterman, Stamford, Conn., assignor to Atlantic Plastics Incorporated, Stamford, Conn., a corporation of Connecticut

Filed June 18, 1962, Ser. No. 70,582

Term of patent 14 years

(Cl. D83—12)

FIGURE 1 is an unassembled view in perspective of the body and cover of an applicator for medicaments or the like, embodying my new design;

The undisclosed side of the nozzle member in FIGURE 1 is substantially the same as the side shown. The bottom of the applicator which is slightly recessed with respect to the sides is flat and plain.

The characteristic features of my new design for the applicator disclosed, resides in the specific configuration of the cap and nozzle member in combination with an ellipsoidal body member, as shown.

I claim:

The ornamental design for an applicator for medicaments or the like, substantially as shown and described.
